UNITED STATES PATENT OFFICE

1,957,383

CHEST

Frank J. Book, Huntington, Ind.

Application November 15, 1933, Serial No. 698,190

2 Claims. (Cl. 217—60)

This invention relates to new and useful improvements in chests, and is especially designed as an improvement in the construction shown in my Patent No. 1,894,849 issued January 17, 1933.

5 The primary object of my invention is to provide novel means for hingedly mounting the seat rail on the chest lid, whereby when the latter is raised, the seat rail will assume an absolutely perpendicular position.

10 In the accompanying drawing, which is for illustrative purposes only and is therefore not drawn to scale:

Figure 1 is a vertical transverse section of a chest, illustrating the application of my invention, the lid closed.

15 Figure 2 is a similar view, the lid raised and Figure 3 is a detail fragmentary view of the seat rail, stay bar and associated parts.

Referring to the drawing for a more particular description of my invention and in which drawing like parts are designated by like reference characters throughout the several views, the numeral 1 designates the chest, 2 the lid which is hingedly connected to the chest in the usual 25 way and 3 the seat rail. The seat rail is hinged at its lower inner edge, as at 4, to the top of the lid and connected at its lower outer surface to the back 5 of the chest, by the stay bar 6.

In the present embodiment of my invention, 30 the stay bar 6 consists of a flat metal elongated strip, comprising a straight upper end portion 7, rigidly secured to the lower outer face of the seat rail 3 by the fastening screws 8, a contiguous outwardly curved or bowed portion 9, which extends over the hinged back edge, as 10, of the lid, and the straight depending lower portion 11, connected at its slotted lower end 12 by means

of the screw 13, with the back 5 of the chest. The slot in the lower end of the stay bar permits the necessary play or limited sliding movement of the latter when the lid of the chest is raised or closed.

60 In practice, when the lid of the chest is raised, the seat rail 3 will assume an absolutely perpendicular position, as illustrated in Figure 2 of the drawing, and, as a result, the chest may be placed near or against the wall and the lid raised, without causing any interference of the seat rail with the wall.

65 From the foregoing description taken in connection with the drawing, it is thought that the construction, operation and advantages of my invention will be readily understood without requiring a more extended explanation.

Having described my invention, what I claim as new and desire to secure by Letters Patent, is:

1. In combination with a chest with a hinged lid, a perpendicular seat rail and means for hingedly mounting the seat rail on top of the lid and slidably connecting the same with the back of the chest, whereby, when the lid is raised, the seat rail will assume an absolutely perpendicular 75 position.

2. In combination with a chest with a hinged lid, a perpendicular seat rail and means for hingedly mounting the seat rail on top of the lid and slidably connecting the same with the back of the chest, whereby, when the lid is raised, the seat rail will assume an absolutely perpendicular 85 position, said means comprising a stay bar rigidly connected at its upper end to the lower outer face of the seat rail and slidably connected at its lower end to the back of the chest. 90
